DESIGN FOR A SIGNBOARD

James H. Landers, Rome, N. Y.

Application April 17, 1935, Serial No. 56,443

Term of patent 7 years

To all whom it may concern:

Be it known that I, James H. Landers, a citizen of the United States, residing at Rome, in the county of Oneida and State of New York, have invented a new, original, and ornamental Design for Signboards, of which the following is a specification, reference being had to the accompanying drawing, forming part thereof.

Fig. 1 is a front elevational view of one-half of the signboard, for the purpose of more clearly showing detail;

Fig. 2 is a front elevational view of the complete signboard on a smaller scale; and

Fig. 3 is an end elevational view.

Fig. 4 is a vertical sectional view taken along the vertical centerline of the signboard.

I claim:

The ornamental design for a signboard, as shown.

JAMES H. LANDERS.
